UNITED STATES PATENT OFFICE

166,966

SIDE MOUNTED LANTERN

Eduard R. Huegel, Brooklyn, N. Y., assignor to
Rambusch Decorating Company, New York,
N. Y., a corporation of New York

Application April 1, 1952, Serial No. 19,146

Term of patent 14 years

(Cl. D48—4)

To all whom it may concern:

Be it known that I, Eduard R. Huegel, a citizen of the United States of America and a resident of the Borough of Brooklyn, in the county of Kings, city and State of New York, have invented a new, original, and ornamental Design for a Side Mounted Lantern, of which the following is a specification, reference being had to the accompanying drawing, forming a part thereof.

In the drawing:

Figure 1 is a side elevational view of a side mounted lantern showing my new design;

Figure 2 is a front elevational view thereof; and

Figure 3 is a top plan view thereof.

I claim:

The ornamental design for a side mounted lantern, as shown.

EDUARD R. HUEGEL.
